CLAIM

The ornamental design for a clipper, as shown and described.

DESCRIPTION

This application makes reference to:
U.S. utility application Ser. No. 14/193,367 filed Feb. 28, 2014. All disclosure and subject matter, including all figures, of the '367, '538, '707 and '527 applications are specifically incorporated in this application as if set forth fully herein.
FIG. 1 is a front right perspective view of an embodiment of a clipper showing our new design;
FIG. 2 is a front elevation view thereof;
FIG. 3 is a rear elevation view thereof;
FIG. 4 is a left side elevational view thereof;
FIG. 5 is a right side elevational view thereof;
FIG. 6 is a top plan view thereof; and,
FIG. 7 is a bottom plan view thereof.
